ATTORNEY

UNITED STATES PATENT OFFICE.

GABRIEL MARTINEZ, OF GRANADA, NICARAGUA.

MATCH BOX.

Application filed February 19, 1924. Serial No. 693,877.

To all whom it may concern:

Be it known that I, GABRIEL MARTINEZ, a citizen of the Republic of Nicaragua, residing at Granada, Rep. de Nicaragua, C. 5 A., have invented new and useful Improvements in Match Boxes, of which the following is a specification.

This invention relates to improvements in match boxes and the like, the general object of the invention being to so form the cover part of the box that the drawer part can only be projected from one end thereof, with means for permitting the drawer part to be pushed upon from the closed end 10 of the box in order to project the same.

Another object of the invention is to provide means for indicating when the box is in upright position so as to prevent spilling of the matches if the box is opened in the 15 dark.

This invention also consists in certain other features of construction and in the combination and arrangement of the several parts, to be hereinafter fully described, illustrated in the accompanying drawings and 20 specifically pointed out in the appended claims.

In describing my invention in detail, reference will be had to the accompanying drawings wherein like characters denote like or corresponding parts throughout the several views, and in which:—

Figure 1 is a view of the box with the drawer in partly open position.

Figure 2 is a section on line 2—2 of Figure 1.

Figure 3 is a view of the blank from which the cover part of the box is formed.

In these views, A indicates the cover part 40 and B the drawer part of a match box. The part B is made as usual but the part A has one end closed by the end piece 1 which is formed with the top part 2. This end

piece is provided with the flaps 3 for engaging the side pieces 4 and with a small flap 5 for engaging the bottom 6. This end piece is provided with an opening 7 so that a finger can be passed through the same to push the drawer part partly out of the cover part. This hole is adapted to be covered 45 with a strip 8 of cloth or the like. A stop 9 is placed in the top 2 and acts to limit the amount of movement of the drawer part though this stop is so formed that the drawer part can be readily pushed into the 50 cover part. A projection 10 is also formed on the top 2 and serves as a means for indicating when the box is in the correct position for opening, thus preventing the box 55 from being opened while it is upside down 60 which might happen at night or in the dark and thus spill the matches.

It is thought from the foregoing description that the advantages and novel features of my invention will be readily apparent. 65

I desire it to be understood that I may make changes in the construction and in the combination and arrangement of the several parts, provided that such changes fall within the scope of the appended claims. 70

What I claim is:—

1. A box of the class described comprising a cover part and a drawer part, one end of the cover part being closed and a strip of flexible material forming part of the closing means. 75

2. A box of the class described comprising a cover part and a drawer part, the cover part being formed with a flap for closing one end of the same, said flap having an 80 opening therein and a strip of flexible material placed over the opening.

In testimony whereof I affix my signature.

GABRIEL MARTINEZ.
